METHOD OF AND APPARATUS FOR TREATING COFFEE

Albert J. Hazle, Jr., Chicago, Ill., assignor to B. F. Gump Co., Chicago, Ill., a corporation of Illinois

Application December 24, 1938, Serial No. 247,600

6 Claims. (Cl. 83—18)

The present invention relates to a method for treating coffee and apparatus by means of which the steps of the method may be practiced, and more particularly to such apparatus and method which may be utilized in connection with the production of coffees having different characteristics, such as steel cut and more finely divided and pulverized coffee.

With the increasing popularity and use of more finely divided and pulverized coffee, as compared with steel cut coffee, it is realized that it would be highly desirable and advantageous to have treating apparatus of a universal character, which could with equal facility be selectively utilized to produce various types of grinds, such as steel cut, semi-pulverized and flour coffee, and in which the amount of comminuted chaff in the finished product may be varied.

While the apparatus and process as described in the above patent is admirably suited and very satisfactory, when utilized in connection with steel cut or granular coffee, it should possess certain other operating characteristics when it is endeavored to use the apparatus in the processing and treating of more finely divided or pulverized coffee.

As a result of the foregoing discoveries, the present invention contemplates as a primary object the provision of a universal coffee treating apparatus which may with equal facility be utilized for treating steel cut coffee, as well as more finely divided and pulverized coffee.

Another and further object of the herein described invention is to provide in a universal coffee treating apparatus, improved means which may be selectively rendered nonoperative or operative to remove chaff that has been liberated during the reduction of the coffee beans.

Still another object of this invention is to provide in apparatus as described herein and including a chaff separating mechanism, a chaff separating mechanism for removing liberated chaff from a stream of material such as reduced coffee, a novel arrangement for returning to the stream any particles of coffee or material which may be taken out with the removed chaff.

In accordance with the general features of the herein described invention, it is proposed to utilize the invention in connection with apparatus having a grinding head of the multiple reduction type, whereby the various size grinds may be selectively produced by adjusting the various reduction rolls by throwing them in and out of grinding position. For example, when it is desired to produce very coarse or cracked coffee, the lower reduction rolls are thrown apart or out of grinding position, thus permitting the coffee to pass therebetween without further reduction. On the other hand, when it is desired to produce what is generally known as "steel

cut," the next lower reduction rolls, which are provided with suitable corrugations, are adjusted to grinding position, the reduction rolls below these being thrown apart or out of grinding position. Further, when it is desired to produce a finer or pulverized grind, all the reduction rolls are set in grinding position. The foregoing procedure may be varied according to the usual practice, depending on the size product desired.

10 As an additional feature, means are provided for removing liberated chaff in the cracked coffee beans in the grinding head by subjecting the stream of cracked coffee particles to an air current which carries the lighter chaff particles to a separating chamber. Of course, in removing the chaff, there is a likelihood that particles of coffee will be carried along with the chaff. Unless these particles are recovered, they will be carried away with the chaff, thereby reducing 15 the efficiency of the apparatus. In order to recover particles of coffee which are carried away with the chaff, the separating chamber is provided with an outlet door which is retained closed by the action of partial vacuum. This door is 20 so arranged that it will automatically open at periodic intervals due to the weight of the accumulation of coffee particles in the separating chamber to permit the coffee particles to return to the grinding head by the inlet conductor for 25 the air stream utilized in removed chaff.

30 Other objects and features of this invention will more fully appear from the following detailed description taken in connection with the accompanying drawings. It is believed that my novel method will be understood from a description of the apparatus and that a detailed description of the process will be unnecessary.

35 In the accompanying drawings which illustrate a preferred form of apparatus and several 40 modifications of certain parts thereof, and in which similar reference numerals refer to similar features in the different views:

45 Figure 1 is an elevational view partly in section of an apparatus embodying the present invention for carrying out my novel process;

Figure 2 is an end view of the same showing chaff separating means connected thereto;

50 Figure 3 is an enlarged fragmentary sectional view taken through the grinding head of the apparatus and showing the cooperative relationship of the chaff removing mechanism therewith, taken substantially on line III—III of Figure 1;

55 Figure 4 is a transverse sectional view through the grinding head at the location of the final reduction rolls, showing the manner in which these rolls may be relatively adjusted to operative and non-operative positions, taken substantially on line IV—IV of Figure 1;

Figure 5 is a fragmentary end view of the apparatus having broken away portions to show the

cooperative relationship between the final reduction rolls and the conveying mechanism in the granulating chamber; and

Figure 6 is a sectional view taken through the grinding head to show further details of the final reduction rolls and their adjusting mechanism taken on line VI—VI of Figure 5;

Figure 7 is a view schematically illustrating an alternative drive arrangement for the grinding head rolls;

As shown on the drawings:

In the illustrated embodiment of the present invention, the apparatus for treating coffee is disclosed as in general embodying a grinding head as generally indicated at A for grinding or reducing the coffee and delivering the reduced coffee mass to a treating mechanism generally indicated at B. As shown in Figure 2, there is associated with the grinding head chaff removing mechanism as generally indicated at C. The grinding head and coffee treating mechanism are supported as a unit upon spaced channel rails 11 and 12 which are connected to and supported upon suitable leg frames 13.

The grinding head, as shown in Figure 3, comprises a casing 14 which forms a grinding chamber and totally encloses the grinding mechanism.

Within the grinding chamber is a wall 15 having vertically spaced concave recesses 16. This wall is connected at its upper end with the casing 14 by means of a sloping portion 17, and at its lowermost end with the casing by means of a horizontal portion 18.

Cracking rolls 19-19 are journaled in the casing and respectively located in the recesses 16-16. These cracking rolls coact with a larger cracking roll 20 which is similarly journaled in the casing. The cracking rolls cooperate to form the first and second reduction stages for cracking the coffee beans and delivering the cracked coffee particles together with liberated light, flaky chaff to a third reduction stage.

The coffee beans are delivered to the grinding head through an inlet opening 21 formed in the top of the casing 14. From the opening 21, the coffee beans are guided to the cracking rolls by a sloping chute member 22 to which a plate 23 is attached that cooperates with a plate 24 upon the member 17 for forming a guide chute. Upon the lower side of the member 22, there is disposed an angle member 25 to which a guard or scraper 26 is secured for contacting the surface of roll 20 and preventing the coffee beans from spreading and moving over the top of the roll. The scraper 26 by virtue of its engagement with the roll 20 also forms an air barrier to prevent the passage of air, as will hereafter become more apparent, from the coffee inlet around the inactive surface portion of the roll 20.

The third reduction stage comprises a pair of rolls 27 and 28 which are journaled in the casing. These rolls are arranged to be driven in opposite directions, and one of the rolls is driven at a greater speed than the other. The surfaces of these rolls are so formed as to provide a further reduction of the cracked coffee particles by a granulating action. As the coffee is discharged from the roll 20 and the lower roll 19, it falls onto a perforated deflector 26' which augments the distribution of the coffee over the rolls 27 and 28.

It will be noted that the portion 18 of the wall 15 may be utilized to support a scraper 29 which has its upper edge closely disposed to the surface of lower roll 19 and its lower edge slightly spaced

from the surface of roll 28. Cooperating with the portion 18 to form baffles between the portions of the casing containing the second set of reduction rolls and the portion of the casing containing the cracking roll, is an inwardly extending and downwardly inclined casing portion 30 which may have a plate 31 attached to its upper surface. The plate 31 is shown as carrying a suitable wiper 32 which may be of leather or other suitable material. This wiper bears against the surface of the roll 27.

Below the rolls 27 and 28 of the third reduction stage, as shown in Figure 4, a fourth reduction stage is provided in the casing by rolls 33 and 34 which are suitably journaled in the casing in a similar manner to the rolls 27 and 28. The fourth stage rolls are preferably of the type having saw tooth corrugations in their surfaces for further reducing coffee granules to a pulverized state. Cooperating with the rolls 33 and 34 are scrapers 35 and 36, as shown in Figure 5, to prevent material adhering to the roll surfaces during the grinding operation. It will be noted that the scrapers 36 guide the material between the rolls and prevent the material from passing around the inactive surfaces of the rolls.

Both the granulating rolls of the third reduction stage and the pulverizing rolls of the fourth reduction stage are so arranged that they may respectively be moved towards and away from each other for the purpose of regulating the extent of reduction of the coffee particles. Moreover, the adjustment of the pulverizing rolls permits movement of these rolls into operative and non-operative relation with the coffee material from the granulating rolls. Thus, with the pulverizing rolls in operative position, the coffee particles from the granulating rolls must pass between the pulverizing rolls and be further reduced, whereas if the pulverizing rolls are moved apart, the coffee particles from the granulating rolls may pass between the pulverizing rolls without being further reduced. It will therefore be apparent that with this arrangement the grinding head may be utilized to selectively produce granulated or steel cut coffee and pulverized or finely ground coffee as desired, and while in the present instance four reduction stages have been described, any desired number of reduction stages may be utilized.

Similar mechanisms are provided for adjusting roll 27 relative to roll 28, and roll 33 relative to roll 34, the latter roll in each case having its journals rigidly mounted in the casing 14. The journals of the rolls 27 and 33 are mounted for movement relative to the casing, and it is thought that a description of the adjusting mechanism as applied to one of these rolls will be sufficient to understand the arrangement.

As shown in Figure 4, the journals of roll 33 are each carried at the outer end of an arm 37 of a bell crank 38 which is pivoted on the casing as shown at 39. This bell crank has an arm 40 substantially at right angles to the arm 37. At its outer end the arm 40 is provided with a bolt 41 threadedly adjustable in a longitudinal direction in the end of arm 40. This bolt has one end arranged to engage the surface of an eccentric 42 on a shaft 43 which extends longitudinally of the casing 14 and is suitably trunnioned for rotative movements. One end of the shaft 43 carries an actuating lever 44 by means of which the shaft may be rotated. Secured to the shaft 43 for rotation therewith is an arm 45 carrying a spring detent pin 46 at its free end which is co-

operatively associated with a plate 47 on the casing, this plate having a series of holes 48 respectively adapted to receive the detent pin 46 in various adjustments of the lever 44.

The end of bolt 41 is urged against the eccentric 42, and the roll 33 is urged toward roll 34 by means of a spring 49 having one end in engagement with one of the journals for this roll and its other end associated with a bolt 50 threadedly supported in the casing. By adjusting the bolt 50, the pulverizing rolls may be engaged with greater or less pressure as desired.

It will be apparent from the foregoing description that by moving the lever 44, the eccentric 42 acts to move the bell crank 38 in either a clockwise or anti-clockwise direction to bring the roll 33 into closer or further apart relationship with the roll 34.

The chaff removing mechanism C is arranged to variably remove chaff from the coffee particles during their passage from the second reduction stage to the third reduction stage, that is, during their passage from the cracking rolls to the granulating rolls.

As shown in Figure 2, a chaff collector 51 is disposed at any convenient location adjacent the apparatus. This collector is provided with a pipe 52 which connects with the outlet of a suction fan housed in a casing 53 supported on the grinding head or in any suitable location. The inlet to the suction fan is connected through a conductor 54 which communicates with the top portion of a box-like structure 55. The box-like structure 55 defines a separator or settling chamber for receiving removed chaff and separating therefrom any coffee particles which may be contained therein and have been removed from the mill.

This part of the chaff removing mechanism, as shown in Figure 3, is supported as a unit on a plate 56 that is removably secured as by thumb bolts 57 to a spacer frame 55' surrounding an opening 58 formed in the casing 14 adjacent the cracking rolls. The spacer frame at its top has a cut-out portion which forms a slot opening 56' for the admission of air into the casing 14 for removing any chaff or coffee particles adhering to the adjacent surface of roll 20. The amount of air admitted at this point is controlled by a closure plate 57' having appropriate transversely extending slots 58' for receiving thumb bolts 59' for guiding the plate movement and securing it in adjusted position relative to the slot opening.

The pipe 54 at its connection with the box-like structure 55 is provided with a contracted open end 59 so that a portion of the inlet air may be taken in by the suction fan without passing through the separating chamber.

The bottom of the separating chamber is formed by downwardly converging bottom plates 60 and 61 for receiving coffee particles. The plate 60 at its lower end margin is provided with a plurality of spaced hinged doors 62 which are each normally maintained in closed position by the partial vacuum created within the separating chamber. The space at the bottom of the chamber adjacent the doors 62 is longitudinally divided by vertical partitions 62' to provide separate outlets for the respective doors so that one door will not interfere with another door when discharging coffee particles or disturb the air intake to such extent as would result in the use of a single large door.

The plate 61 is inwardly deflected at its point of convergence with the plate 60 to form a plate 75

portion 64 which cooperates with a downwardly spaced plate 65 to form an air inlet channel having its entrance disposed below the door 62. The innermost end of the plate 65 is terminated adjacent the plate 31. The innermost end of plate 64 is secured to an inclined plate 66 which has its lowermost edge disposed adjacent the surface of roll 27 and cooperates with plate 31 to form a continuation of the inlet air channel. It will be apparent that inlet air will pass over the surface at roll 27 into the space between the cracking rolls and the granulating rolls where it may come in contact with the cracked coffee particles and particles of light chaff contained therein.

Air is taken from this space and conducted through a channel formed by plate 66 and an upwardly spaced plate 67. The upper marginal edge of plate 67 is secured to the plate 56 and at the point of communication of this part of the air channel with the interior of the box-like structure 55 is provided with a deflector 68 for directing the air, chaff, and any coffee particles contained therein towards the bottom of the separating chamber.

The amount of suction in the separating chamber, and consequently the amount of air being drawn into the grinding head may be regulated by means of a slide door 69 on the forward side of the box-like structure, this door being slidably supported so that it may be raised and lowered to admit variable amounts of air to pass directly into the separating chamber and thence through conductor 54, or by closing this door the intake air must enter the mill through the inlet air channel previously described.

By thus varying the amount of air passing into the grinding head, varied amounts of chaff may be removed, as desired. Any coffee particles which may be conducted to the separating chamber will obviously accumulate in the bottom and be separated from the lighter particles of chaff which are drawn toward the top of the separating chamber and pass off into the chaff collector. As the particles of coffee accumulate and their weight against the door increases, the door 62 will open and permit the particles of coffee to be reconducted through the inlet air channel back to the granulating rolls. As soon as the coffee particles have passed from the separating chamber to the air inlet channel, the door 62 will again close until a sufficient accumulation of coffee particles has been attained to cause the door to open again.

Should the apparatus be desired without this additional feature of the chaff remover, the plate 56 may be removed and a solid plate secured over the opening 58 in its stead. Removal of plate 56 also carries with it the parts forming the inlet air channel.

The suction to fan 53 may also be further controlled by a valve gate 70 in the conductor pipe 54 as shown in Figure 2.

The granulating mechanism B for treating the coffee after it comes from the grinding head, as shown in Figures 1 and 5, includes an elongate trough-like casing 71 which is supported on and between the channel rails 11 and 12, this casing being provided with a rounded bottom. The casing at its inlet end communicates directly with the outlet from the grinding head and receives the coffee and chaff particles passing the rolls 33 and 34. The top of the casing 71 from the grinding head to the outlet end of the casing is provided with a closure plate 72 removably se-

cured in position closing the top of this part of the casing by means of lug and cam connectors 73.

The casing is closed at its ends by end closures 74 and 75 and is longitudinally separated into compartments 76, 77, and 78 by partitions 79 and 80 disposed adjacent the outlet end of the casing. It will be noted that the compartment 76 is open throughout a portion of its top for communication with the grinding head, but is closed by the removable cover from the grinding head to the partition 80. Likewise compartments 77 and 78 are closed at their tops by the cover plate 72.

Extending longitudinally of the casing 71 and supported upon suitable journals 81 and 82 respectively secured to the end closures 74 and 75 is an elongate shaft 83. This shaft extends through the end closures and the partitions 79 and 80.

For continuously conveying the coffee mass containing coffee particles and light chaff particles away from the inlet end of the casing 71 and to prevent the throwing of coffee particles back against the pulverizing rolls and accumulation of coffee particles around the outlet of the grinding head, particularly in the case of pulverized coffee particles, there is provided a ribbon screw conveyor at this end of the casing which will smoothly advance the coffee toward the discharge end of the casing without subjecting it to agitation. The ribbon screw conveyor comprises an elongate metallic ribbon 84, which is spiraled about the shaft 83 and secured in spaced relation to the shaft at spaced points throughout its length by means of radially extending arms 85 which have their outermost ends secured to the ribbon by means of suitable flat plates 86. It will be noted that the several turns of the conveyor are formed from a single ribbon of material. The ribbon is of such length that the spirals may be continued to a point lying within the covered portion of compartment 76.

In constructing this conveyor, many difficulties were encountered before a conveyor was finally produced which would not throw the coffee mass when run at a relatively high speed, for example 415 to 445 R. P. M.

It was found that a satisfactory conveyor which would advance the material substantially as a whole at a uniform rate and would not throw the material could be obtained by constructing the conveyor with each helix formed at substantially an angle of 13° relative to a cutting plane at right angles to the shaft, and by making the spiral pitch substantially less than the spiral diameter.

At the operating speed of the conveyor, the coffee mass will be moved away from the inlet end of the casing 71 continuously and at the rate at which the material is being delivered from the grinding head.

Within the covered portion of the compartment 76, and also within the compartment 77 there are provided a plurality of whipping arms 87 which are arranged in staggered relation on the shaft 83. These arms have terminal blades 88 which are directed at an angle that will cause the coffee mass received from the ribbon conveyor to be advanced at intervals.

Due to the change from continuous advancement to interval advancement of the coffee mass, the coffee mass will be accumulated within the covered portion of compartment 76 and subjected to the whipping action of the arms 87, which will agitate the coffee particles and set up an abrad-

ing action which comminutes the chaff and commingles it with the coffee particles so that the chaff is rendered invisible by being concealed in the coffee particles.

5 It has been found that the accumulation of coffee particles, particularly in the case of pulverized coffee, and the subjection of these particles to a whipping action for a relatively short period of time is of prime importance when 10 treating pulverized coffee. By treating the coffee as just described, excessive beating and resulting discoloration is prevented.

As the coffee accumulates in compartment 76 adjacent the partition 80, it is freed to pass into 15 compartment 77 through an opening 89 in the partition 80, as shown in Figure 9. It will be noted that the opening 89 is disposed above the bottom of the casing 71 so that there must be a substantial accumulation of coffee before it may 20 pass into compartment 77. It has been found that the arms 87 are more effective in the agitation and beating of a substantial mass of coffee. The coffee in compartment 77 is subjected to a 25 further beating action and is discharged therefrom into compartment 78 as soon as there has been a sufficient accumulation to open a hinged gate or door 90 in partition 79, as shown in Figure 1, this door being normally held in closed position by the action of gravity on a suitable 30 weight 91 carried by the door.

From compartment 78, the coffee particles containing the comminuted particles of chaff are discharged through an outlet nozzle 92 at the bottom of the compartment.

35 Referring to Figure 2, the leg frames 13 are preferably secured at their bottoms to a platform base 102 which also provides a support for a driving motor 103. The driving shaft of this motor carries a driving sprocket 104 which is 40 connected to a sprocket 105 on the shaft 83 by means of a chain 106.

The rolls 33 and 34 are respectively driven 45 through sprockets 107 and 108 by means of a chain 109 which is driven from a sprocket (not shown) on shaft 83, this chain also being trained over an eccentrically adjustable chain tightening sprocket 110.

The rolls 27 and 28 are similarly provided with 50 sprockets 111 and 112 over which a chain 113 is trained and driven by a separate sprocket (not shown) on the shaft 83. An eccentrically adjustable tightening sprocket 114 is likewise provided in this case.

The cracking rolls, as shown in Figure 1, are 55 driven from the opposite ends of roll 28 through a suitable connection within a housing 115, in conjunction with other connections contained within a housing 116, as shown in Figure 5, in the conventional manner.

60 As shown in Figure 1, it is preferred to provide an enclosing casing 117 for concealing the driving sprockets and chains associated therewith for the rolls.

As an alternative driving arrangement to that 65 just described, there is schematically illustrated in Figure 11 a single chain drive for the rolls 27, 28, 33 and 34. In this arrangement the roll driving sprockets 107, 108, 111 and 112 and the idler sprockets 110 and 114 are in the same plane.

70 Instead of utilizing a double chain drive for these sprockets, a single chain 118 is trained over them, this chain being driven from a single sprocket on the shaft 83.

A single chain drive for these rolls is very desirable, since it enables standardizing of the roll 75

journals and permits their being interchanged.

From the foregoing description, it will be apparent that the present invention provides improved apparatus and method for treating coffee; coffee treating apparatus of universal character which may be utilized for producing different grinds of coffee, such as steel cut and pulverized; which may have variable amounts of chaff removed therefrom; which is particularly adapted for the treating of finely ground or pulverized coffee and is so arranged that the coffee particles will not become overbeaten and thereby discolored; which embodies novel chaff removing mechanism; and which utilizes novel conveying and agitating mechanism for comminuting the chaff and commingling it with the coffee particles.

I am aware that numerous details of the construction of the apparatus and details of the process carried out by such apparatus may be varied through a wide range without departing from the principles of this invention, and I, therefore, do not purpose limiting the patent granted hereon otherwise than necessitated by the prior art.

I claim as my invention:

1. In a coffee mill including a casing, means in said casing for cracking coffee beans, means defining an air inlet channel for conducting air from the exterior of the casing into the stream of cracked coffee and chaff contained therein for removing the chaff and any coffee particles carried along with the chaff, means defining an air outlet channel for conducting the air together with the removed chaff and any coffee particles contained therein to the exterior of the casing, a chamber outside the casing connected to said air outlet for separating the chaff and any coffee particles contained therein, and means for returning the separated coffee particles to the air inlet channel for return with the inlet air to the stream of cracked coffee.

2. The process of preparing coffee which comprises the subjecting of coffee beans to multiple stages of reduction for effecting a coffee stream between certain of said stages containing granular or pulverized coffee particles and liberated chaff particles, passing an air stream between an air inlet path and an air outlet path, the air stream during its movement between said paths engaging the coffee stream for removing chaff therefrom together with any coffee particles carried along with the chaff, separating the removed chaff and any coffee particles carried along with it from the coffee stream and thereafter conducting the separated coffee particles by the inlet air path to the coffee stream to return them to substantially the same location in the coffee stream from which they were removed.

3. In a coffee treating apparatus, a casing having a coffee inlet, a rotating cracking roll in communication with said inlet, and a rotating reduction roll below the cracking roll, means for removing from the stream of cracked coffee chaff and any coffee particles that may be carried along therewith and returning the coffee particles removed with the chaff back into the stream prior to its reaching the reduction roll, said means including an inlet air conductor extending into said casing, an air outlet conductor extending into said casing, said conductors having adjacent open inner ends disposed to pass the air flowing therebetween into the coffee stream between the crack-

ing and reduction rolls, and means connected with said conductors for separating the removed chaff and coffee particles and delivering the separated-out coffee particles to the air inlet conductor for return to the coffee stream.

4. In a coffee treating apparatus, including a casing having a coffee inlet and a rotating cracking roll in communication with the inlet, means for removing chaff from the cracked coffee and any coffee particles that may be carried along with the removed chaff, said means including an air outlet conductor extending past the cracking roll in close proximity to its cracking surface and having an open end adjacent the cracked coffee discharged from the cracking roll, the other end of said conductor communicating with the exterior of the casing, said conductor cooperating with the cracking roll surface to form an air passage embracing a portion of the cracking roll surface adjacent the cracked coffee discharge therefrom, barrier means for separating said coffee inlet and said air passage, and an air inlet for admitting air into the casing between said barrier and said passage for movement through the passage in a direction opposed to the direction of rotation of the cracking roll for picking up coffee and chaff particles adhering to the roll surface.

5. In a coffee treating apparatus including a casing having a coffee inlet, a rotating cracking roll in communication with said inlet, and a rotating reduction roll below the cracking roll, means for removing from the stream of cracked coffee chaff and any coffee particles that may be carried along therewith and returning the coffee particles removed with the chaff back into the stream prior to its passage of the reduction roll, said means including an air exhaust conductor extending into the casing and having an inlet end disposed between said rolls adjacent the stream of cracked coffee from the cracking roll, air inlet passages respectively embracing portions of the inactive surfaces of said rolls, barriers associated with said rolls and positioned to respectively oppose movements of the inlet air at each passage around the associated roll in a direction away from the inlet end of the exhaust conductor, and means for separating the chaff and coffee particles from the exhaust conductor and delivering the separated-out coffee particles to the air inlet passage associated with the reduction roll for return through said passage to the cracked coffee stream.

6. The process of preparing coffee which comprises subjecting coffee to a multiple of stages of reduction with a coffee stream comprising granular coffee particles and liberated chaff flowing between said stages, impelling an air current into contact with said coffee stream after it has left one of said stages and between adjoining stages of reduction for removing therefrom liberated chaff, separating from said removed chaff coffee particles removed with the chaff, conducting the separated coffee particles back to the coffee stream flowing between said stages of reduction, reducing by a further of said stages of reduction said returned coffee particles along with the main bulk of the coffee particles flowing in said stream, and controlling the return of the removed coffee particles to the coffee stream by the accumulation of the removed particles of coffee at a point removed from but adjoining the area of reduction.

ALBERT J. HAZLE, JR.
